DESIGN FOR A DESK STAND FOR A HAND TELEPHONE

Henry Dreyfuss, Pasadena, Calif., and Robert H. Hose, Mountainside, N. J., assignors to Bell Telephone Laboratories, Incorporated, New York, N. Y., a corporation of New York

Application February 11, 1948, Serial No. 144,404

Term of patent 14 years

(Cl. D26—14)

To all whom it may concern:

Be it known that we, Henry Dreyfuss and Robert H. Hose, citizens of the United States, residing at Pasadena, in the county of Los Angeles and State of California, and at Mountainside, in the county of Union and State of New Jersey, respectively, have invented a new, original, and ornamental Design for a Desk Stand for a Hand Telephone, of which the following is a specification, reference being had to the accompanying drawing, forming a part thereof.

Fig. 1 is a perspective view of a desk stand for a hand telephone, showing our new design;

Fig. 2 is a top plan view of the desk stand; and

Fig. 3 is a rear elevational view of the desk stand.

We claim:

The ornamental design for a desk stand for a hand telephone, as shown.

HENRY DREYFUSS.
ROBERT H. HOSE.
